Primary Examiner—Sandra S. Snapp(74) *Attorney, Agent, or Firm*—Kilpatrick Stockton LLP**CLAIM**

I claim the ornamental design for a bottle, as shown.

DESCRIPTION

FIG. 1 is a perspective view of a bottle comprising the present invention.

FIG. 2 is a front elevational view of the bottle shown in FIG. 1.

FIG. 3 is a rear elevational view of the bottle shown in FIG. 1 and FIG. 2.

FIG. 4 is a side elevational view of the bottle shown in FIG. 1, FIG. 2, and FIG. 3.

FIG. 5 is another side elevational view of the bottle shown in FIG. 1, FIG. 2, FIG. 3, and FIG. 4.

FIG. 6 is a top plan view of the bottle shown in FIG. 1, FIG. 2, FIG. 3, FIG. 4, and FIG. 5; and,

FIG. 7 is a bottom plan view of the bottle shown in FIG. 1, FIG. 2, FIG. 3, FIG. 4, FIG. 5, and FIG. 6.
